DUMPING CAR

Arthur Wesley Lancaster, Orillia, Ontario, Canada, assignor to E. Long Limited, Orillia, Ontario, Canada, a company of Ontario, Canada

Application November 23, 1945, Serial No. 630,186

1 Claim. (Cl. 105—255)

1

This invention relates to dumping cars and particularly to a door and door operating structure therefor.

It is an object of the invention to provide a dumping car particularly designed for use in mines and on railways and the like wherein the contents of the car are dumped through the side thereof and in which the swinging door is controlled throughout its length to lift evenly.

A further object of the invention is to provide a device of this kind wherein the door or doors of the car are caused to swing in such a manner that the lower extremity of the door will move away from the door frame to an increased degree relatively to the upper portion of the door, thereby to facilitate the door opening and eliminate unnecessary friction between the door and the contents of the car.

A further object of the invention is to provide a simple and efficient door opening means designed readily to cooperate with the doors and the car for discharge of its contents.

A still further object of the invention is to provide a door lifting handle or projection which will cooperate with the lifting means to provide for proper engagement of the door lifting means with the door, even though such lifting means may not be properly centered in respect to the latter.

With these and other objects in view, the invention generally comprises a car door structure, swingably mounted on the side of a car and preferably extending throughout the length of the car, designed to be swung upwardly from lower normal position, including a control shaft extending throughout the length of the door and link means connected therewith whereby to maintain a corresponding degree of movement of each end of the door to cause it to raise and lower evenly. Preferably the door structure includes a means for causing the lower portion thereof to move outwardly from the door frame to a greater degree than the upper portion thereof and also includes a novel lifting means designed efficiently to cooperate with the door to raise the latter. A means for centering the lifting means in its engagement with the door is also preferably included.

The invention will be clearly understood by reference to the following detailed specification taken in conjunction with the accompanying drawings.

In the drawings:

Fig. 1 is a side elevation of a mine car illustrating the mounting of a door along the side of the car.

2

Fig. 2 is an end elevation of Fig. 1 showing one-half the car in section and illustrating the swinging movement of the door from the lowered position.

5 5. Fig. 3 is an end elevation partly in section of an alternative type of construction and showing a cooperating door lifting structure in combination therewith; and

Fig. 4 is an enlarged fragmentary side elevation of the projecting means on the doors of each car for engagement by the lifting means in the lifting operation thereof.

Referring to the drawings, A indicates a suitable dumping car for use in mines and on railways and the like which is generally of an elongated rectilinear character in top plan view. According to the present invention, the cars are preferably open along each side between the upper peripheral framework 10 and the base 11. 10

15 20. In the type of car shown in Figs. 1 and 2, the base 11 is formed of the oppositely sloped base plates 12 which slope downwardly from their point of juncture 13 to the lower outer edge of the car. A door B is swingably mounted to close this open

25 side of the car.

The pivotal mounting of the doors is accomplished by a pair of upper link units 14 and a pair of lower link units 15 which are disposed at opposite ends of the car and are pivotally mounted on the car as at 16 and 17, respectively, pivotally connecting at their opposite ends with the longitudinally extending shafts 18 and 19, respectively, which extend throughout the length of the car as shown in Fig. 1. These shafts may project through a suitable flange 20 projecting laterally from the ends of each door as shown particularly in Fig. 2.

30 35 The link units 15 are longer than the link units 14 and since they are pivoted at 17 from a point below and vertically aligned with the pivot point 16 of links 14, it will be obvious that when the door is swung from closed to open position, the longer links 15 will tend to cause the lower edge of the door to swing outwardly from the lower portion of the car thereby to facilitate the ready movement of the door and eliminate substantial friction with the contents thereof, thus to permit the ready and free discharge of the contents of the car.

40 45 50 The raising of the doors of cars of this type is usually accomplished automatically, one form of means being an inclined ramp disposed at the dumping point beside the tracks on which the car travels and designed to engage the cooperating member on the doors to effect the lifting.

operation at the proper time as the car passes the dumping point. In the present instance, centrally of the doors towards the lower edge thereof a wheel member 21 is rotatably fastened on a suitable stub shaft and projects laterally from the doors to an extent designed to engage the inclined guideway of a ramp positioned beside the tracks on which the car travels. In order to provide for the even lifting of the door under these particular conditions, according to the present invention, the link structure from which the doors are pivotally hung is controlled so that each link unit disposed at opposite ends of the car must operate with the other. This is accomplished by mounting, on the shafts 22 which extend throughout the length of the car underneath the base plates 12, the levers 23 which are keyed to the shafts at each end of the car and are designed to connect with the vertically disposed link member 24 in each instance. The link members 24 in turn are pivotally connected as at 25 to the links 14. Thus, when each door is raised it is obvious that their motion at each end must be identical by reason of the fact that the shafts 18 and 19 extend throughout the length of the door, that the shafts 22 extend throughout the length of the car, and that the levers 23 and links 24 operatively connect the shafts to control the even lifting of the door. The shafts 18 and 19, particularly, perform the function of reinforcing the doors in the lifting operation so that any tendency towards warping or distortion of the doors is restrained.

The alternative form of structure shown in Fig. 3 operates in the same manner. In this construction, the doors 26 and 27 are swingably mounted by means of the pairs of links 28 and 29 disposed at each end of the car, the links 28 being shorter than the links 29 to provide for outward swinging of the lower edge of the doors to a greater degree as previously described in connection with Figs. 1 and 2. These are pivoted as at 30 and 31 on the ends of the car at spaced apart points vertically aligned with one another. The links 28 are designed to be keyed to the longitudinally extending shafts 32 disposed through the upper end of each door and extending the length of the door as in the case of the shafts 18 in Figs. 1 and 2. The links 29 are pivoted to the doors as at 33 either by such a longitudinally extending shaft or by straight pivotal connection, it being preferable to employ the latter where the percussive contact of ore and the like with the lower portion of the door would tend to jam the longitudinally extending shaft when disposed on the inside. The shaft connection 32 and/or a lower corresponding shaft when employed forms a means for causing the uniform lifting of each end of the door when it is caused to swing upwardly, thus providing for even lifting of the door throughout its length.

In Fig. 3 I show a preferred form of cooperating door lifting mechanism which embodies the pneumatic lifting cylinders C and the cooperating control cylinder D which controls the swinging movement of the lifting means. The lifting cylinders C include the piston rods 34 projecting downwardly therefrom and terminating in the hook-like members 35. These latter are designed to engage the door lifting projections 36 carried at the center of each door, the specific structure of the projections being defined hereinafter.

The lifting cylinders C and the control cylinder D are operated from separate manual controls (not shown) positioned at the dumping station where the lifting mechanism is also disposed.

It is not necessary to disclose the pneumatic operating system since such a system is well-known, it being sufficient to say that one operating control will cause the raising or lowering of the pistons in cylinders C while another operating control, conveniently positioned, may be operated to cause the piston in cylinder D to raise and lower its piston rod 37.

The cylinders C and D are suspended from a suitable suspension rod or the like 38 by means of a suitable clevis such as the clevises 39 and 40 which pivotally connect with the protruding lugs 41 and 42 by means of the transverse wrist pins 43 and 44. Thus, it is clear that the cylinders may swing in an arc longitudinally of the direction of the car and in an arc transversely of the car.

When the car reaches dumping position and is disposed between the downwardly hanging piston rods 34 and the cylinders C, the latter are disposed in a lowered position below the door lifting projections 36 and by operating the manual control for the cylinder D, the piston rod thereof is raised. By means of the link connections 45 pivotally connected with the lower end of the piston rod 37 at one end and at their opposite ends with the lower ends of the cylinders C, the latter are caused to swing inwardly, as generally indicated in dotted lines, so that the hook-like members 35 are brought into engagement with the door lifting projections 36 as the piston rods 34 are caused to rise in the cylinder C as the latter are operated. The action is aptly illustrated by the dotted lines in Fig. 3 so that as the doors are caused to swing to the upper dotted position, the contents of the car is discharged through the side openings thus exposed. In this action the doors swing outwardly to a greater degree at the bottom than at the top as previously described and the contents are, therefore, cleanly and readily discharged while the doors are lifted uniformly from the central point of mounting of the lifting projections 36.

The lifting projections take the form, as particularly illustrated in Fig. 4, wherein the lifting bar or shoulder 46 is upwardly sloped inwardly from its ends to a maximum height 47 at the center of the projection. This forms a guide means for centering the hook-like elements of the piston rod 34 since it is apparent that if the hook-like elements engage the projection to one side or the other of the center, the guide slope of the projections will cause the hook-like members to center in the projections. Moreover, the swinging movement of the cylinders C and cylinder D in the longitudinal direction of the car will permit ready centering as well as a clean engagement or disengagement with the door lifting projections where the car is slightly in motion during the commencement of the engagement between the hook-like members 35 and the door lifting means or the disengagement of these members from the door lifting means.

From the foregoing, it will be apparent that I have provided a simple type of door construction and door operating mechanism through which ready discharge of the contents of the cars is effected, while eliminating any tendencies of the doors to jam or distort and providing for the ready engagement or disengagement of the door lifting means in a practical manner.

What I claim as my invention is:

In a dump car having a fixed body with at least one open side, the combination of, a sloping base plate in the body sloping toward the lower outer

edge of the open side thereof, a door upwardly and outwardly swingable to uncover the open side, a pair of spaced apart arms extending from individual pivotal connections at each end of the body for pivotal connection to the ends of said door substantially at the upper and lower extremities thereof, a through shaft extending longitudinally of the body below said base plate, a crank arm extending from either end of said shaft on the exterior of the body, and a link pivotally connected to the free end of each crank arm and having its other end pivotally connected between the ends of one of the spaced apart arms at each end of the body, said crank arms being fixed to said shaft to provide operative connection between the spaced apart arms from one end of the body to the other.

ARTHUR WESLEY LANCASTER.
